Primary Examiner — Richard Edgar*Assistant Examiner* — Carolyn W Davis(74) *Attorney, Agent, or Firm* — CANTOR COLBURN LLP(57) **CLAIM**

The ornamental design for a dehumidifier, as shown and described.

DESCRIPTION

FIG. 1 is a front perspective view of a dehumidifier, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of encircled portion 8 in FIG. 1;

FIG. 9 is an enlarged view of encircled portion 9 in FIG. 5; and,

FIG. 10 is another front perspective view thereof showing a state of use in which an air outlet is opened.

The even-dash broken lines illustrating portions of the dehumidifier form no part of the claimed design. The dot-dot-dash broken lines encircling enlarged portions of the claimed design form no part of the claimed design.

1 Claim, 10 Drawing Sheets(56)
